SHOE AND CUSHIONING MEMBER OR MIDDLE SOLE THEREFOR

Application filed November 20, 1928. Serial No. 320,684.

This invention is an improvement in boots and shoes and the principal object of the invention is to provide such shoes with a cushion member adapted to be interposed between the inner and outer soles of the shoes which member will be flexible, uniformly yieldable, and will uniformly support the inner soles at all points.

The present invention is particularly designed for use in connection with boots and shoes of the so-called "Goodyear welt" type in which the upper is secured to the sole by a welt, and a chamber or space would be left between the inner and outer sole and the welt; and the specific object of the present invention is to provide a cushioning member which may be of any desired thickness and will uniformly yieldingly fill the said chamber or space and may be readily applied to the shoe in the making thereof and be secured thereto by the same means which attaches the welt to the outer sole.

A further object of the invention is to enable the cushioning member to be made of any desired thickness to increase the cushioning effect, to any desired extent as compared with other shoes in which the so-called cushions are merely space or bottom fillers.

The invention includes both the novel construction or formation of the cushioning member and also the shoe or boot sole embodying such novel cushioning members.

In the accompanying drawings I have illustrated the at present preferred form of the cushioning member, and part of a welt shoe of which such cushioning member forms a part, and I will explain the invention with reference to said drawings to enable others to fully understand and use the same.

In the claims the novel constructions and novel combinations of parts for which protection is desired are summarized.

In the drawings:

Fig. 1 is a bottom plan view of the cushioning member detached.

Fig. 2 is a transverse section of the cushioning member on the line 2—2 Fig. 1.

Fig. 3 is a transverse section through a welt shoe, having my novel cushioning member embodied in the sole portion thereof.

Fig. 4 is a detail sectional view showing how the thickness of the cushioning member of the shoe, such as shown in Fig. 2 can be increased without altering the inner sole, the welt or the outer sole of such shoe.

The shoe may be of any suitable make but I prefer so-called "Goodyear welt" shoes. Customarily such shoes have an upper U to the edge of which is attached the welt W and have an outsole O and an inner sole I. The welt W is ordinarily first attached to the inner sole I by stitches s; and the welt and outer sole are then united by one or more rows of stitches S of thread or wire. Sometimes the inner and outer soles are connected by pegs instead of stitches, but the particular means (pegs or stitches) for securing the upper and welt together and for securing the welts and sole together are not features of the present invention, and may be such as preferred by the shoe maker. The outsole O may consist of one or more layers of leather or other suitable material, as may be desired.

In building such a shoe a space or chamber C is formed between the inner sole I and the outsole O, the thickness or height of such chamber ordinarily corresponding with the thickness of the welt W. Such chamber has heretofore been filled in various ways; sometimes with felt, sometimes with rubber or with leather or composition, and various kinds of cushioning material have been used to fill this space in order to more or less yieldingly support the inner sole I. My invention provides a successful cushioning member whereby the inner sole is uniformly yieldably supported at all points; and which cushioning member can be secured in position by the means which unite the welt and the outsole. Such a cushioning member is shown detached in Figs. 1 and 2 and in section in Figs. 3 and 4.

This cushion member comprises a thin and flexible top portion 1 which corresponds in contour to the plan contour of the chamber or space C under the insole I and surrounded by the welt W. This top portion is connected at its margins by thin flexible portions 1^a with a marginal flange 1^b of considerable thickness, and which flange corresponds in plan contour with the plan contour of the

welt W and the flange 1^b underlies the welt W when the cushion member is in position.

The plane of the top surface of portion 1 lies above the plane of the top portion of the flange 1^b, the difference in level of the two planes being approximately equal to the thickness of the welt W at the point where the upper is stitched to the welt. The plane of the bottom surface of the flange 1^b is of course separated from the plane of the upper surface of the top portion 1 a distance corresponding to the thickness of the welt W plus the thickness of the flange 1^b.

Depending from the under surface of the top portion 1 of the cushion member are a series of inverted pyramidal shaped protuberances 1^c the bases of which practically abut where they spring from the lower surface of the top portion 1, and these protuberances diminish in cross-section as they depend away from the top portion 1, and the apexes, or lower ends, of these protuberances are in the same plane as the lower surface of the flange 1^b and the lower ends of these protuberances directly contact with the upper surface of the outsole O, when the parts are properly assembled and united, as shown in Fig. 3.

The cushion member as a whole, including the top portion 1, the protuberances 1^c and the flange 1^b as above described, is preferably formed or molded integrally of rubber, or suitable resilient yielding composition or material. When made of rubber the flange 1^b is preferably vulcanized or more solid than the cushion proper, to enable a smooth finish to be made on its edge at the outer edge of the sole.

The outsole may be of leather, rubber or any material used for that purpose. The welt, outsole and flange of the cushion are preferably first cemented to hold them in place while they are being assembled, then they are preferably secured together by what is known as Goodyear stitching. In assembling the parts after the welt is stitched to the upper the cushioning member is placed in position between the welt and the flange 1^b interposed between the welt and the outsole O and then the welt, flange 1^b and outsole are united by stitching or pegging or in the usual manner; the flange 1^b forming a part of the edge of the sole. The stitches S go through the welt, flange and outsole.

The insole I is made of flexible leather or other materials used for making insoles. The protuberances 1^c are so close together that their bases practically abut and together form a solid platform so that the insole will not buckle up or wrinkle and form ridges. The flange of the cushion is made wide enough to extend to the outer edge of the welt and the outsole. Also the ends of the flange are beveled next to the shank of the shoe as at 1^a to form inclines to stitch over and make

neat joints. When the cushion is used the shoe apparently has a double outsole when finished.

It will be observed that the protuberances 1^c are arranged practically in parallel series and support the inner sole at all points equally and uniformly. The tapering of these members allows for expansion or distortion under pressure of the foot of the wearer, and the air confined in chamber C assists in distributing and equalizing pressure on the inner sole, and also assists in preventing interchange of heat through the cushioning member between the inner sole and outsole.

The central portion of the cushion member projects above the flange 1^b and is made to fit in the chamber of the welt shoe ordinarily made. In the ordinary welt shoe the chamber or space between the inner and outer soles are not deep enough to enable a thick member to be employed, but by the use of the flange 1^b as described the depth of the chamber or space between the inner and outer sole can be decreased or increased as desired to any desirable thickness.

The flange 1^b around the outer end of the cushioning portion proper enables me to make the cushioning portion (1, 1^c) of any desired thickness by simply varying the thickness of the flange in accordance with the desired thickness of the cushion proper.

In the ordinary shoe cushion members can only be made as thick as the depth between the inner and outer sole and this depth is entirely dependent upon the thickness of the welt, and the upper; but by increasing the thickness of flange 1^b I can correspondingly increase the thickness of the cushioning member proper.

Figures 4 indicates how the cushioning portion illustrated in Figs. 1, 2 and 3 can be made much thicker by simply increasing the thickness of the flange 1^b. This simple means of increasing the thickness of the cushion member is obviously of great value in increasing the cushioning effect. A thicker flange deepens the chamber C in the shoe and makes the protuberances 1^c longer, giving a much thicker and consequently more resilient cushion member than has heretofore been possible.

I claim:

1. A cushioning member for shoes having inner and outer soles; comprising a thin top portion adapted to contact with the inner sole and having a multiplicity of closely adjacent inverted-pyramidal protuberances of substantially uniform height depending from the underside of said top portion and integral therewith, the upper larger ends of said protuberances substantially abutting, and the smaller contracted ends of the protuberances adapted to contact with the upper surface of the outer sole.

2. For a shoe having inner and outer soles

and a welt, a cushioning member comprising a top portion having protuberances on its under side and a marginal flange in a plane below the plane of the top portion, the top surface of the top portion being adapted to contact with the under surface of the inner sole, and the lower ends of the protuberances being adapted to contact with the upper surface of the outer sole; and the flange being adapted to be confined between the welt and outer sole.

form of a truncated pyramid and the lower ends of the protuberances being in the plane of the lower surface of the said flange, and contacting with the upper surface of the outer sole; said flange being secured to and between the welt and outsole. 70

3. A shoe having inner and outer soles and a welt, a cushioning member comprising a top portion having protuberances on its under side, and a marginal flange, the upper surface of the top portion contacting with the under surface of the inner sole, each of said protuberances being solid and in the form of a truncated pyramid, the lower ends of the protuberances being in the plane of the lower surface of the said flange and contacting with the upper surface of the outer sole; and said flange being attached to and between the welt and outer sole.

25 4. In combination with a shoe having inner and outer soles and a welt connected to the upper and outer sole; a cushioning member comprising a thin top portion adapted to contact with the inner sole, and a multiplicity 30 of closely adjacent inverted pyramidal protuberances depending from the underside of the top portion and integral therewith, the larger upper ends of said protuberances substantially abutting, and the smaller contracted ends of each of these protuberances depending below the welt and contacting with the upper surface of the outer sole.

5. In a shoe the combination of an upper, an insole, an outsole and a welt connected to the upper and outsole and defining a chamber 40 between the insole and the outsole; with a cushioning element comprising a top member snugly fitting within said chamber and having protuberances on its under side, and a 45 marginal flange, the top member contacting with the under surface of the inner sole; each of said protuberances being solid and in the form of a truncated pyramid; the lower ends of the protuberances being in the plane of the lower surface of the said flange and contacting with the upper surface of the outer sole, said flange being secured to and between the welt and outsole.

6. In a welt shoe the combination of an 55 upper, an insole, an outsole and a welt connected to the upper and defining a chamber between the insole and the outsole; with a cushioning element comprising a top member snugly fitting within said chamber having 60 protuberances on its under side, and a marginal flange on a plane below the plane of the upper surface of the top member; the upper surface of the top member contacting with the under surface of the inner sole, each 65 of said protuberances being solid and in the
